UNITED STATES PATENT OFFICE.

ROWLAND T. WALES, OF SEWAREN, NEW JERSEY.

MOLD FOR CONCRETE CONSTRUCTION.

1,308,269.

Specification of Letters Patent.

Patented July 1, 1919.

Application filed August 5, 1915. Serial No. 43,732.

To all whom it may concern:

Be it known that I, ROWLAND T. WALES, a citizen of the United States of America, residing at Sewaren, in the county of Middlesex and State of New Jersey, have invented certain new and useful Improvements in Molds for Concrete Construction, of which the following is a specification.

This invention provides certain improvements in molds for use in building structures of concrete or similar material, or for facing or covering structures with such material. The particular construction of molds to which these improvements apply, consist of the following: There are plates against which the concrete is molded and they consist of boards or panels. They are held in position by a framework or series of supports or studs. The studs may be secured and held in position by any usual or suitable method for securing and holding such members. Plates are held in position by means of locks which engage the studs. Plates are adjustable and movable relatively to the studs and adjustable into and out of position without affecting the studs. Plates are likewise adjustable and movable without affecting adjoining plates, except in special cases. Each lock is both adjustable and movable relatively to both plates and studs and without moving studs, other locks or other plates than the plates immediately held by it. Such a construction permits using the same plates and locks repeatedly in different parts of the same framework of studs before a job is completed. It also permits taking down the studs, after stripped of plates, and using the same supports again in another part of the job. While two studs are in any one position, a plate can be used between them repeatedly at subsequently higher levels, each removal of the plate being made after the concrete behind it has become only sufficiently hard to stand up in the small area which the plate has covered. The construction of molds described in the foregoing has the following advantages:

1. Uses less mold material on a single job.
2. Uses the same mold material repeatedly and without destruction on successive jobs.
3. Is erected and dismantled quicker and with less labor.
4. Permits easy placing and supporting of any iron reinforcement within the mold space before the plates are locked in posi-

tion. With no plates to obstruct the workmen, the individual parts of the reinforcement can be handled separately and fastened directly and accurately into their final positions and without previous assembling. 60

5. Possesses all advantages of panel molds without sacrificing the strength and accuracy possible by using studs as in other molds.

This invention provides certain new and useful improvements pertaining to the construction described in the foregoing, and has made it more practical. Some of the objects accomplished by these improvements are given in the following: 70

1. Improved means for holding locks from moving laterally.

2. Improved form of stud adapted for engagement by the improved locks shown herein and in other applications filed by me. 75 The improvements give maximum strength of stud with minimum weight and cost of manufacture.

3. An improved corner stud.

4. An improved plate of sheet metal with 80 maximum strength and minimum weight and thickness of sheet metal.

5. An improved metal plate adapted to form a surface on concrete which will hold plaster.

6. An improved means by which a given number of locks will support a variable number of plates under ceilings of different spans between walls. 85

Various sheet metal shapes are applicable 90 for manufacturing the studs according to the stock of shapes available or economical and according to the character of work for which the mold will be used. Likewise, different parts of the locks and of other parts 95 of the invention may be varied in construction or in combination, according either to requirements or to economy in manufacture. A number of examples are illustrated here-with, all of which embody essential features 100 of this invention.

Figure 1 is a horizontal section showing a general view including a corner of a wall.

Fig. 2 is a partial vertical section. It shows a stud in side elevation showing a 105 lateral side of the stud.

Fig. 3 is a partial horizontal section on line 3 of Fig. 2.

Fig. 4 is a partial view of an outside corner stud in elevation, and a corner lock, 110

This view is looking at the arrow marked 4 in Fig. 1.

Fig. 5 is an end view of a plate partly cut away.

5 Fig. 6 is a longitudinal section through a channel showing the construction at one end of the plate.

The marks in the following indicate details of studs and attached parts.

10 A are Z bars of sheet metal extending longitudinally of the stud and between the space engaged by the locks and the mold space. There are two, each one being disposed in a lateral side of the stud, as shown. Between

15 the two there is a longitudinally extending space adapted to admit tie rods f at any level and as shown in Figs. 1 and 2.

A² is a wood member adjacent the mold space and adapted to form a surface on

20 concrete which will hold plaster. It is also adapted for nailing to it the members t and t¹ shown in Fig. 2.

B are channel shapes of sheet metal extending longitudinally of the stud and constituting its main strength. There are two in a stud, as shown, and adapted to admit between them a tie rod f shown in Figs. 1 and 2.

C and C¹ are bolts which hold parts of a

30 stud together as shown.

D are spacers or small metal members which hold members A separated from members B. They are perforated to admit bolts C which hold them as shown. The space

35 which separates the parts A from B extends longitudinally of the stud and is adapted for engagement by locks at any point not obstructed by the spacers D.

F are flanges on A to prevent plates K

40 from entering the mold space and prevent cement from entering between the stud and the plates.

H are flanges on Z bars A and extend inwardly of the stud. Conjointly with

45 flanges J, the bolts C and the spacers D, they constitute a means within and close to the lateral sides of the stud for holding its members together without obstructing the movement of plates at the lateral sides of

50 the stud. The bolts C are disposed as near as possible to the lateral sides of the stud to prevent the lateral sides of the stud from being bent apart at the opening between A and B.

55 J are flanges on B for the purpose explained under H.

S are short bars or metal members for stiffening and bracing the lateral sides at the outward part of the stud. They are

60 bolted to the flanges T by the bolts C¹. They are distributed at intervals longitudinally of a stud as indicated in Fig. 2 by C¹.

T are flanges on B to give additional strength and rigidity. They provide a

65 means for connecting the opposite sides by

means of S and C¹ within the lateral sides of the stud where neither S nor T will obstruct the movement of plates.

e in Fig. 2 is a channel-shaped stringer shown in vertical cross section. It is for 70 holding studs at proper distances apart on the same side of a wall just as stringers like it are used in other molds or concrete forms. Similar stringers e¹ are shown in plan in

Fig. 1.

e¹ are stringers of wood just explained under e.

f in Figs. 1 and 2 are tie rods such as are used in other forms to hold studs in position. They extend transversely of the 80 mold and generally pass each through two studs, one on each side of the wall. They are often substituted by wire.

t at the right of Fig. 2 are spacing blocks or sticks nailed to the wood faces on A² of 85 the studs. These blocks t keep the studs separated at the proper distance from structural steel, or at the proper distance from studs on the opposite side of a wall or from any support or object, as required. They are 90 shown herein to illustrate another advantage of the wood member A² on the stud.

t¹ at the right of Fig. 2 are horizontal strips nailed to the wood face of the stud to leave ornamental depressions in the concrete resembling masonry lines, and are shown herein to illustrate another advantage of the wood member A² on the studs.

t² at the right of Fig. 2 are vertical strips extending between t¹ t¹ and for the same 100 purpose given above for t¹.

The marks in the following indicate details of locks which engage the studs and hold the plates adjacent the mold space.

P is the part of a lock which carries a 105 movable part Q and transmits the load to the stud.

Q is a movable part shown in the form of a screw which is moved relatively to P inwardly and outwardly of the mold and will 110 prevent outward movement of plates when Q is in position.

W is a bent end of Q which serves as a handle for turning Q.

P¹ is a lug on P to prevent it from moving laterally of the stud.

P² is an outward extending arm on P to carry other parts of the locks, as shown. Conjointly with parts which bear on the stud it prevents the lock from moving out 120 of position.

P³ is an arm on P² which bears against a lateral side of the stud and conjointly with P² holds the lock in position, as explained under P². P³ is cut at its end to admit Q. P³ bears on the stud at a greater distance from the point at which P bears on the stud, than the distance between that point and Q where P receives the load. The lock thus has great power to resist the load. The 130

body portion of the lock generally comprises one or more of the parts P , P^1 , P^2 and P^3 .

P^6 in Fig. 3 is a spring attached to the lock and which enters the stud with P as shown. It prevents the lock from slipping out of position when not under pressure outward of the mold from K . A slot in P^6 surrounds Q and permits free movement.

P^{50} in Figs. 1 and 3 is a thumb screw or 10 clamping screw which turns within P^2 near P and has its end adapted to bear on a lateral side of a support as it is shown bearing against B . It draws the lug P^1 laterally and securely into position. It is adapted to 15 prevent the lock falling from position when there is no load bearing on the lock. When P^{50} is used for said purpose the spring P^7 is not necessary and may be eliminated. P^{50} is also adapted to prevent Q from bearing 20 laterally and directly against a support and thus disposes Q sufficiently beyond the end of K to hold K securely. For this latter purpose the thumb screw P^{50} could be replaced by a bolt with lock nuts which secure 25 it rigidly to P^2 .

The marks in the following indicate details which pertain to plates.

K are boards which are fastened together in standard panels.

L (see at the right of Fig. 2 where a plate 30 is partly cut away; also see Fig. 3) is a strip facing a panel at its edge and connecting the boards of the panel together. It is adapted to bear against the flanges F 35 on the studs.

M (see at the right of Fig. 2 where a plate is partly cut away; see also Fig. 3) is an angle reinforcing the end and the edge of one face of a plate in a similar manner as L . 40 M may or may not connect boards together in one panel, but may extend across the ends of unattached boards and hold them in position.

M^2 in Figs. 5 and 6 is an angle similar to 45 M described above. It reinforces the end of a metal plate or panel, connects its parts and provides a bearing surface for locks. One wing of it extends transversely of both the mold face and the channels (v) and 50 forms the end face of the plate. Its other wing covers part of the open side of said channels and thus forms a face adapted to bear against said locks.

M^4 in Figs. 5 and 6 are short angles riveted in position and connecting M^2 with other parts of the plate as shown.

M^5 in Fig. 5 is a metal strap reinforcing the side of a metal plate which is not reinforced by M^2 .

v in Figs. 5 and 6 are channel shapes of thin sheet metal which, when connected side by side, form a strong and durable plate of minimum weight and with a face which will not warp or be bent out of plane.

v^7 in Figs. 5 and 6 is a lap cut and bent on

the end of a flange on a channel and is bolted to M^2 , as shown.

v^8 in Fig. 6 is a recess at the end of the face of the channels v and is for engaging flanges or members similar to F in Fig. 3. 70

v^9 in Figs. 5 and 6 is a lap cut in the end of the web of the channel v and bent so that it may be bolted to M^2 as shown.

Plates formed of channels as illustrated in Figs. 5 and 6 are also advantageous for 75 molding some ceilings or downward facing surfaces.

The marks in the following indicate details in corner studs, corner locks and corner plates, and are shown in Figs. 1 and 4. 80

M^6 is a bearing plate connecting and reinforcing the edges of the boards or plates K^4 which meet at an outside corner of a wall. The screws Q of the corner locks bear on M^6 and thus hold K^4 in position. M^6 is 85 shown as loosely nailed to K^4 and may be easily removed from K^4 when not in the mold.

M^7 is an iron angle disposed in the inside corner formed by the boards or plates K^5 90 which are connected at the inside corner of a wall. It may or may not be fastened to K^5 . The screws Q of the corner locks bear on M^7 , as shown, and thus hold K^5 against pressure from the mold space.

R is a corner stud supported in a crotch formed by the stringers e^1 outside the outside corner of the wall. It is made of sheet metal, is hollow, and has an open side facing toward the corner of the wall. It has wings 100 G , diverging from its open side and bearing against the stringers e^1 , as shown.

R^1 is a corner stud similar to R and is shown supported by stringers e^1 inside the inside corner of the wall. It has wings G^1 105 similar to G on R .

K^4 is explained under M^6 .

K^5 is explained under M^7 .

g is a spring on a lock. When a lock is placed in position, g and part of Q , as 110 shown, are inserted in the open side of R or R^1 . g presses on the inner sides of R or R^1 and holds the lock in position before concrete is poured and causes pressure on the lock.

P^8 is a small plate or bar which carries the screw Q and in which Q turns. It is placed across the open side of R or R^1 at any desired level and the screw Q on being turned moves toward or from the corner of the mold 120 space to the proper position for holding plates K^4 or K^5 in position.

h is a handle on Q for turning it. In Fig. 4 it is partly cut away to show how it may be held in position by lock nuts on its opposite sides.

Any detail, element or part shown on apparatus illustrated in the drawings, may be added to apparatus illustrated in applications Nos. 802,867 and 41,683 filed by me 130

Nov. 25, 1913, and July 24, 1915, pertaining to molds for concrete construction. Any such element may also be eliminated from the apparatus where illustrated if unnecessary for any work.

In molding some concrete ceilings or some downward facing surfaces and especially those in some subways, a stud can be used as a joist and either with or without the 10 flanges F.

What I claim is:—

1. A mold for concrete comprising plates and studs adjacent the mold space, locks adjustable longitudinally of the studs and 15 gaging the studs, a part of a lock which engages a stud being movable within the stud and longitudinally of it, flanges adjacent the mold space and diverging laterally of a stud and overlapped by the ends of said 20 plates, a lateral side of a stud comprising two sheet metal surfaces, each of which is part of a different member which extends longitudinally of the stud and is kept separate from the other said member by spacers 25 fastened between them at different positions distributed longitudinally of the stud and maintaining between said members an opening which extends longitudinally of the stud and is engaged by said locks, the said sheet 30 metal members being bent inwardly of the stud at said opening and held rigidly on the opposite sides of said spacers.

2. A mold for concrete comprising plates and studs adjacent the mold space, locks adjustable longitudinally of the studs and engaging the studs, a part of a lock which 35 engages a stud being movable within the stud and longitudinally of it, flanges adjacent the mold space and diverging laterally of a stud and overlapped by the ends of said plates, a lateral side of a stud comprising two sheet metal surfaces, each of which is part of a different member which extends longitudinally of the stud and is kept separate from the other said member by spacers 40 fastened between them at different positions distributed longitudinally of the stud and maintaining between said members an opening which extends longitudinally of the stud and is engaged by said locks, the said sheet 45 metal members being bent inwardly of the stud at said opening and held rigidly on the opposite sides of said spacers, there being another opening which extends longitudinally of the stud and divides all sheet metal parts 50 on one lateral side of the stud from all sheet metal parts on the other lateral side and is adapted to admit, without obstruction of metal at any level between said spacers, tie 55 rods which extend transversely of the mold and hold the stud in position.

3. A mold for concrete comprising plates and studs adjacent the mold space, locks adjustable longitudinally of the studs and engaging the studs, a part of a lock which en-

gages a stud being movable within the stud and longitudinally of it, flanges adjacent the mold space and diverging laterally of a stud and overlapped by the ends of said plates, a lateral side of a stud comprising two sheet metal surfaces, each of which is part of a different member which extends longitudinally of the stud and is kept separate from the other said member by spacers fastened between them at different positions distributed longitudinally of the stud and maintaining between said members an opening which extends longitudinally of the stud and is engaged by said locks, the said sheet metal members being bent inwardly of the stud and held rigidly on the opposite sides of said spacers by means substantially equivalent to bolts and disposed within and close to the lateral sides of the stud to prevent the two said members from being bent apart at said lateral sides.

4. A mold for concrete comprising plates adjacent the mold space and comprising a series of supports, locks engaging the supports and holding the plates in position, a plate comprising a plurality of parallel adjoining sheet metal channels combined in one rigid body, the flanges of each channel extending outwardly of the mold and transversely of said supports and thus giving sufficient strength to permit the use of very thin sheet metal, each end of the plate comprising a metal angle, one wing of which extends transversely of the mold face and of said channels and forms the end face of the plate, the other wing of said angle covering part of the open side of said channels and thus forming a face adapted to bear against said locks.

5. A mold for concrete comprising plates adjacent the mold space and comprising a series of supports, a plate comprising a plurality of parallel adjoining sheet metal channels combined in one rigid body, the flanges of each channel extending outwardly of the mold and transversely of said supports and thus giving sufficient strength to permit the use of very thin sheet metal, the channels being combined so that a recess is formed at each end of the plate where adjacent members overlap it.

6. A mold adapted to form a corner of concrete, the mold comprising a corner stud, a corner plate and a corner lock for holding the corner plate in position adjacent the mold space, the corner stud being disposed at a distance from the corner plate, the lock comprising a metal plate which bears against the corner stud, and carries a screw which on being turned moves toward and from the corner of the mold space, said screw, when in adjustment, being adapted to hold the corner plate from moving toward the corner stud.

7. A mold adapted to form a corner of concrete, the mold comprising a corner stud, a corner plate and a corner lock engaging the corner stud and for holding the corner plate in position adjacent the mold space, the corner stud being disposed at a distance from the corner plate, the lock comprising a small metal plate which bears against the corner stud, is adjustable longitudinally of the corner stud and carries a screw which on being turned moves toward and from the corner of the mold space, said screw, when in adjustment, being adapted to hold the corner plate from moving toward the corner stud, said stud being hollow with its open side facing toward the corner of the mold space.
8. A mold adapted to form a corner of concrete, the mold comprising a corner stud, a corner plate and a corner lock engaging the corner stud and for holding the corner plate in position adjacent the mold space, the corner stud being disposed at a distance from the corner plate, the lock comprising a small metal plate which bears against the corner stud, is adjustable longitudinally of the corner stud and carries a screw which on being turned moves toward and from the corner of the mold space, said screw, when in adjustment, being adapted to hold the corner plate from moving toward the corner stud, said stud being hollow with its open side facing toward the corner of the mold space, and adapted to admit means for holding the lock from dropping out of position when not held by pressure from the load.
9. A mold for concrete comprising plates, a series of studs and a plurality of locks engaging each stud and for holding the plates adjacent the mold space, said locks being capable of interchangeable distribution longitudinally of the stud and each lock having a body portion for engaging the stud and a screw carried by the body portion and movable relatively to the body portion inwardly and outwardly of the mold, said body portion also carrying a clamping screw the end of which bears against a lateral side of the stud and prevents the lock moving parallel to the surface of the mold space, said body portion also having a lug which is disposed within the stud, extends outwardly of the mold and prevents the lock moving laterally of the stud, said lug being drawn laterally and securely into position by said clamping screw.
10. A mold for concrete comprising a plate formed of permanently connected channels, the webs of such channels forming an unbroken mold surface.

In witness whereof, I have hereunto signed my name in the presence of two subscribing witnesses.
